UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

THREAD-WAXING DEVICE.

1,128,670.

Specification of Letters Patent. Patented Feb. 16, 1915.

Original application filed August 25, 1905, Serial No. 275,741. Divided and this application filed June 22, 1912. Serial No. 705,169.

To all whom it may concern:

Be it known that I, ANDREW EPPLER, a citizen of the United States, residing at Lynn, in the county of Essex and State of

5 Massachusetts, have invented certain new and useful Improvements in Thread-Waxing Devices; and I do hereby declare the following to be a full, clear, and exact description of the invention, such as will enable 10 others skilled in the art to which it appertains to make and use the same.

This invention relates to improvements in thread waxing devices for sewing machines.

The object of the invention is to produce 15 an improved thread waxing device in which the temperature of the wax may be more easily and accurately regulated than in the devices heretofore constructed.

With the above object in view a feature 20 of the invention contemplates the provision in a thread waxing device having a steam chamber and a wax pot located adjacent to the steam chamber, of means for permitting a draft of air to flow between the wax pot 25 and the steam chamber. The said means preferably has provision for regulating the amount of air which flows between the steam chamber and the wax pot.

In the accompanying drawings illustrating 30 the invention in its preferred form, Figure 1 is a side elevation partly in section of a thread waxing device and associated parts, and Fig. 2 is a detail sectional view 35 of the wax stripper taken on the line 2—2

of Fig. 1. The present invention is a division of application Serial No. 275,741, filed August 25, 1905 upon which Patent No. 1,030,880 issued July 2, 1912. Inasmuch as the stitch forming mechanism of the machine disclosed in said application forms no part of the present invention, no illustration or description of said mechanism is made in this application.

45 The thread waxing device illustrated in the drawings comprises a steam chamber 1 having a central wax pot space for receiving the wax pot proper 2. The wax pot 2 is made smaller than the central chamber in 50 the wax pot and a damper 3 at the bottom affords means for admitting air through holes therein to the wax pot chamber. By opening the damper more or less a larger or smaller amount of air is permitted to pass

up through the wax pot chamber and thus 55 the temperature of the wax may be very nicely regulated and boiling thereof be prevented. The upper end of the wax pot 2 is provided with a flange which rests upon the upper surface of the casing of the steam 60 chamber 1. To allow for the circulation of the air entering through the damper 3 the upper surface of the casing of the steam chamber is cut away at intervals, as indicated in dotted lines in Fig. 1 at 10. The 65 thread passing up from the wax pot passes through the stripper 4 consisting of a rubber gasket and a follower 5 for compressing the rubber gasket to cause it to strip more or less wax from the thread. The follower 5 is 70 provided with a groove in its upper end which is adapted to receive the collar of the adjusting bolt 6. By screwing the adjusting bolt 6 up and down the follower 5 is raised and lowered. This is regarded as an improvement over the use of a screw thread 75 on the follower which has in the past caused considerable trouble by the sticking of the gasket in the thread. The thread passes into the wax pot from a suitable source of supply 80 and is guided through the wax pot by means of a guiding eye formed at the lower end of a rod 11 projecting downwardly into the pot from the bracket 12 in which the stripper is mounted. As the thread passes 85 out of the pot it is guided by the stripper. From the stripper the thread passes over the tension wheel 7, a tension spring adapted to be compressed by the hand wheel 8 is employed for applying resistance to the wheel, 90 and a lever 9 is provided by means of which the tension may be thrown off. The thread from the tension wheel runs through the thread tube 10 on its way to the stitch forming devices. 95

Having explained the nature and object of the invention, and having specifically described the preferred embodiment thereof, what is claimed is:

1. A thread waxing device for wax thread 100 sewing machines, having, in combination, an annular steam chamber provided with a wax-pot space, a wax-pot located in such space, thread guiding devices for conducting the thread through the wax pot, and 105 means for permitting a draft of air to flow through the wax-pot space.

2. A thread waxing device for wax thread

sewing machines, having, in combination, a steam heated chamber, a wax-pot located adjacent to said steam chamber, thread guiding devices for conducting the thread through the wax pot, and means for permitting a draft of air to flow between the wax-pot and the steam chamber.

3. A thread waxing device for wax thread sewing machines, having, in combination, a steam chamber, a wax-pot adjacent thereto,

thread guiding devices for conducting the thread through the wax pot, and means for permitting a draft of air to flow between the steam chamber and the wax-pot having provision for regulating the amount of such air. 15

ANDREW EPPLER.
